UNITED STATES PATENT OFFICE.

JACQUES BOHLI, OF OBACH, SOLOTHURN, SWITZERLAND, ASSIGNOR TO FIRM SCINTILLA, OF SOLOTHURN, SWITZERLAND.

ROTOR FOR MAGNETO-ELECTRIC MACHINES.

1,385,038.

Specification of Letters Patent. Patented July 19, 1921.

Application filed November 6, 1918. Serial No. 261,430.

To all whom it may concern:

Be it known that I, JACQUES BOHLI, a citizen of the Swiss Republic, residing at Obach, Solothurn, Switzerland, have invented certain new and useful Improvements in Rotor for Magneto-Electric Machines, of which the following is a specification.

By suitably shaping the pole pieces of the rotor for magneto electric machines it is possible to produce such a time course of the induced current as will enable the range of variation of the point of ignition to be adjusted up to the limits of any desired but limited angle.

The present invention has for its object to provide means of attaining a considerably wider range of variation of the point of ignition. With this object the trailing edge of the pole is provided on its side next to the poles of the magnet with a part composed of magnetically conducting material which is separated from the poles by a layer of non-magnetic material. This arrangement has the effect that as the edge of the pole trails, that is to say, moves away from the yoke, the number of lines of force passing from the magnet into the yoke is not reduced suddenly to zero, but owing to the transmission of lines of force through the magnetically conducting part located next to the pole, the said number is first reduced to a medium value which is then gradually diminished to zero.

This resulting retardation of the variation in the number of lines of force causes also a retardation in the diminution of the induced current, whereby it is possible to get

a range of variation of the point of ignition extending up to the limits of the largest angles required in practice.

An embodiment of this invention is illustrated by way of example in the accompanying drawings.

The magnet rotating in the direction of the arrow between the pole pieces of the yoke carries on the side of the trailing edge of each of its N and S poles a part a_n and a_s , respectively, composed of magnetically conducting material. These two parts are fixed to a carrier f inserted between the two poles and are separated from their respective poles by intermediate air gaps b_n and b_s , respectively.

This invention is applicable both to apparatus comprising stationary pole pieces and to apparatus comprising rotating armatures.

What I claim is:

In an ignition generator the combination with an induced member comprising a yoke and spaced pole pieces of magnetic material of an inducing member positioned between said pole pieces and relatively movable thereto, and having magnetically polarized projections equal in number to the pole pieces, and auxiliary pole tips of magnetic material located on the trailing edges of the rotor poles and magnetically insulated therefrom, whereby the reluctance of the flux path is gradually varied during the revolution of the rotor.

In testimony whereof I have signed my name to this specification.

JACQUES BOHLI.
